ASPHALT PERMEABILITY MEASUREMENT
APPARATUS

William H. Ellis, El Segundo, and Robert J. Schmidt, El Cerrito, Calif., assignors to California Research Corporation, San Francisco, Calif., a corporation of Delaware

Filed June 28, 1961, Ser. No. 120,358
2 Claims. (Cl. 73—38)

The present invention relates to a method of determining permeability, in situ, of construction materials such as concrete without requiring removal of samples, as by coring and the like. More particularly, this invention is directed to a method and apparatus for measuring the vapor permeability of materials such as asphalt concrete by isolating a limited area of the finished and undisturbed surface from the atmosphere and flowing air therethrough to measure its permeability in situ.

It is a particular object of the present invention to provide a method and apparatus for measuring in place the degree of compaction of an asphalt concrete, so that such material may be rolled or tamped to a desired degree while it is still sufficiently plastic to permit further working. By such in-place measurements, for example, it is possible to control compaction to a degree where the asphalt concrete is substantially water impervious, but still vapor pervious.

In carrying out the method of the invention, a limited area of the surface of the material, such as asphalt concrete, is isolated under a vapor space formed preferably by a fluid chamber that is sealable to the surface of the material. A pressure differential, sufficient to create a flow of air through the material, is then established between atmosphere and the vapor space. Desirably, this pressure differential is measured by a gauge connected to the vapor chamber. The rate of flow of air at the set pressure differential is then measured over a period of time sufficient to establish equilibrium flow conditions for fluid flow through the isolated area. In a preferred form of apparatus, such pressure differential is created by an enclosed liquid reservoir system having a vapor space connected to the vapor chamber, so that measured amounts of liquid moving into or out of the reservoir may be timed. The vapor space in the reservoir system is accordingly altered to create the desired pressure differential between atmosphere and the fluid chamber sealed to the surface of the concrete. The rate of fluid movement in the reservoir system will thus be a measure of the rate of flow of vapor through the cement. This measurement is directly correlatable to permeability of the material.

There has long been a need for a method of determining the degree of compaction of asphalt concrete while it is still in its plastic condition, so that it can be rolled or tamped to a proper degree without waste of time and materials. Heretofore, it has been the practice to compact such asphalt concrete to a degree that is determined by its surface appearance. Such a procedure is an art that depends upon the supervisor's experience rather than upon a defined method of measuring degree of compaction. It is known that the useful life of asphalt pavements may be increased by limiting the rate of transfer of oxygen, water, and microorganisms from the surface to the interior of the material, and the escape of volatile constituents from the interior to the surface. This transfer of material into and out of asphalt concrete can be minimized by properly compacting for minimum permeability. To reach such a minimum, it is necessary to have a method of optimizing the amount of compaction applied to the material.

2

Heretofore, it has been common to determine the percent of theoretical compaction of the material after it has cooled and hardened. This is done by taking a sample of the raw material and compacting it into a core with a known force. A sample of the hardened material is then cut as a core from the finished concrete. The ratio of the density of the second core to the first is expressed as a percent of theoretical compaction. This value is in fact only a measure of the air voids in the finished concrete, and not a measure of its permeability to fluid flow. Obviously, such a procedure is not suitable for determining the degree of compaction while the mixture is still hot and can be further rolled or compacted to achieve optimum permeability of the finished material.

While the present apparatus is described as being useful for the performance of a method of measuring permeability, and degree of compaction of asphalt concrete in situ, it will also be apparent that the permeability measuring equipment may be used for measuring, in situ, other large horizontal or vertical surfaces whose permeability is of importance, under undisturbed conditions and without requiring removal of samples or plugs. Other materials to which the apparatus can be applied for such measurements are Portland-cement concrete, or materials treated with impregnating fluids, such as timber used for telephone poles, railroad ties, and the like.

Further objects and advantages of the present invention will become apparent from the following detailed description taken in conjunction with the accompanying drawings.

In the drawings:

FIG. 1 is a schematic representation of a permeability apparatus constructed in accordance with the present invention and adapted to perform the method.

FIG. 2 is an alternative arrangement of the apparatus, arranged to apply vacuum across the pressure measuring chamber.

FIG. 3 is a schematic representation of the apparatus of FIG. 1 in use as a permeability measuring device for cores, and a core adapter therefor.

FIG. 4 is a graph showing the correlation of permeabilities of pavements in situ, as measured with the arrangements shown in FIGS. 1 and 2, with the permeability of pavement cores, as measured by the apparatus shown in FIG. 3.

FIG. 5 illustrates a preferred construction of a rapid ring-sealer arrangement for a permeability measuring chamber.

Referring now to the drawings and in particular to FIG. 1, there is illustrated a preferred form of apparatus for carrying out the method of the present invention. As there shown, a limited area of the surface of the concrete is isolated in place and without removing a sample under a vapor space, formed by dome 12. Rim 13 of dome 12 is sealed by grease 14 or other readily adherent materials, so that the compacted surface of the concrete is enclosed under this fluid chamber. A predetermined pressure differential between atmosphere and the space under dome 12 is created by the liquid reservoir arrangement comprising sump chamber 15 and flow measuring chambers 17 and 19. As indicated in the drawings, all of the reservoir chambers 15, 17, and 19 are desirably constructed of translucent materials, such as glass, but it is possible to make them of opaque materials, such as metal, if sight level gauges are incorporated with the apparatus.

As will be apparent from the arrangement in FIG. 1, a pressure gauge, represented by manometer 21, is interconnected to vapor chamber, or dome, 12 by conduit 23. Desirably, manometer 21 is mounted adjacent the pair of liquid metering reservoirs 17 and 19, so that a predetermined pressure differential can be established within the

limits of the fluid flow rates available with the volumes of metering reservoirs 17 and 19. In a preferred form, metering chamber 17 has a volume of 350 milliliters, while upper section 25 and lower section 26 of metering chamber 19 are each of 1 liter capacity.

With the desired pressure differential established by the permeability of cement 10 and with the rate at which fluid flows out of metering chambers 17 and 19 controlled respectively by valves 27 and 29, the in-place permeability of pavement 10 may be measured in units of milliliters per minute per square inch. The single unknown to be measured under these conditions is the time required for a fixed volume of liquid to flow from the metering chambers 17 and 19 into the sump reservoir 15. Time is most conveniently measured by an operator with a stop watch.

To initiate operation of the apparatus, liquid such as water in sump 15 is raised into one, or both, of the sample measuring reservoirs 17 and 19 by the application of air pressure to vapor space 30 at the top of sump 15. In FIG. 1, this air pressure supply is indicated as a gas sampling bulb 32. Bulb 32 is, in effect, a rubber bladder with suitable check valves at its intake end 33 and its output end 34. Pressure exerted by bulb 32 is applied through suitable ports in three-way control valve 36, which interconnects the bulb with tube 37, which in turn communicates with vapor space 30. At the same time, valve 36 shuts off communication to vapor dome 12 by way of tube 39. Valves 27 and/or 29 are then opened so that water in sump 15 can be pumped upwardly into measuring reservoirs 17 and 19. When a desired volume of liquid is trapped in the reservoirs 17 or 19, valves 27 or 29 are again closed and three-way valve 36 turned to the position indicated in FIG. 1. In this position, vapor space 30 in sump 15 communicates with vapor dome 12 through tubes 37 and 39. Then one of the valves, 27 or 29, say 27, is opened sufficiently to permit water to flow out of reservoir 17 to raise the level in sump 15. This flow forces air, or vapor, out of space 30 into dome 12 and thence downwardly through a volume of concrete 10 enclosed by seal 14 around rim 13. The pressure at which air flows through this volume of concrete 10 is indicated by manometer 21. Obviously, the air flow rate will be dependent upon the permeability of the concrete and the pressure differential established by the flow of liquid from reservoir 17 into sump 15. The liquid flow can be adjusted so that the pressure differential is at a desired value, say .15 inch, as indicated in the example in FIG. 1. The time required for a known volume of liquid to flow is then measured. Preferably, an operator measures the time required to displace 50 milliliters by noting the change in level between the 50-milliliter marks 18 on reservoir 17. This time-and-volume measurement to detect rate may be made automatically with a photoelectric cell and light source. Light from the source may either transmit through the liquid or reflect from the surface to one or more photocells set to detect movement of liquid between selected reference levels on reservoir 17. The rate is then recorded against time on a chart or strip recorder.

Where the permeability of vapor in concrete 10 is considerably higher than can reasonably be measured by flow of water from measuring reservoir 17, it is preferable to measure liquid flow with measuring reservoir 19. The two spherical volumes 25 and 26 are desirably one liter volume each, to give a total volume of two liters (2,000 milliliters). As indicated, the vapor space over the top of reservoirs 17 and 19 is selectively vented to atmosphere through valve 41, which controls air flow through tubes 42 and 43, connected respectively to reservoirs 17 and 19.

The reservoir system, including units 17 and 19 and sump 15, and manometer 21 may be mounted in a carrying case of about 2 cubic feet volume, so that the entire unit may be used at the construction site, such as roads, parking facilities, or other construction jobs. Tubes 23 and 39 provide necessary air pressure and flow connections to vapor dome 12, which is then mounted in a suitable lo-

cation on the surface of the asphalt concrete then being compacted. Desirably, several measurements are made in succession at selected locations on the surface to obtain a statistically reliable value.

Referring now to the arrangement shown in FIG. 2, it will be noted that, as compared to FIG. 1, tube 39 has been moved to port 45 and control valve 41, and tube 37 can be vented to atmosphere by three-way valve 36 and port 38. Additionally, conduit 23 has been moved from pressure-measuring tap 24 on manometer 21 to vacuum-measuring tap 22. It will be seen that, with this arrangement, a slight vacuum can be applied to the limited area below vapor dome 12 by releasing fluid in measuring reservoir 17 for return into sump 15. Thus, the pressure differential applied across the limited volume of the in-situ sample of concrete 10 may be either vacuum, as in FIG. 2, or pressure, as in FIG. 1.

FIG. 3 illustrates apparatus for measuring the vapor permeability of a cylindrical core taken from a building material, such as asphalt concrete, with the same form of apparatus illustrated in FIGS. 1 and 2. However, in the apparatus of FIG. 3, vapor dome 12A has been modified by removing rim 13 (FIG. 1), so that the cylindrical portion 11 of dome 12A is substantially continuous with the diameter of the pavement core 10A. Glass dome 12A is then sealed to core 10A by a rubber sleeve 50 which has an internal diameter only slightly larger than core 10A and the cylindrical wall 11, so that the latter may be easily inserted into sleeve 50. Ends 51 and 52 of sleeve 50 are then turned back over the ends of a cylinder 54 constructed of glass or the like. The outer diameter of rubber sleeve 50 is smaller than the inner diameter of cylinder 54, so that the unit comprising core 10A, dome 12A, and sleeve 50 easily inserts into cylinder 54 and leaves an annular space therebetween. In this way, an air pressure seal is formed by connecting an air pump, such as gas sampling bulb 55, to the annular space through conduit 57 and three-way valve 59. By reducing the pressure in the annular space, sleeve 50 shrinks around core 10A and dome 12A. This core adapter can then be used to measure the permeability of a standard pavement core using either the pressure-applying apparatus of FIG. 1 or the vacuum apparatus of FIG. 2.

We have found that permeability measurements made by the present method correlate closely with values obtained with cores cut from the completed concrete. In particular, it is surprising that the vertical permeability of a relatively small area, such as that enclosed by dome 12 or 12A, is not greatly affected by the horizontal permeability of the concrete. FIG. 4 shows this relationship. It is a graph of permeabilities of asphalt pavements measured in place versus the vertical, or transverse, permeabilities of pavement cores taken from the same material. These permeabilities were measured in milliliters per minute per square inch, with the apparatus of FIGS. 1 and 2. By use of this correlation, the values measured on the cores, or in place, may be converted to units readily understood in construction of asphalt concrete.

FIG. 5 is a vertical view, partially in cross section, of apparatus for rapidly isolating a desired area of concrete. This unit is particularly useful on freshly laid, hot asphalt concrete. It functions in the same manner as domes 12 and 12A of FIGS. 1, 2, and 3, with the exception that the former units may be sealed to the surface, when cold, with polyethylene, calking compound, or wax that will easily strip off after each test. In the FIG. 5 apparatus, the vapor dome, indicated generally as 60, includes a cup portion 61 adapted to be vapor-sealed to the vapor-permeable surface of concrete 10 by a sealant, such as grease 14. The sealant is confined within annular space 62 by a pair of O rings 63 and 64 mounted in grooves 65 and 66, respectively, in the bottom lip or sealing face 67 of unit 60. Grease 14 is extruded in a ring through an annular screen member 69 by grease gun 70 of conventional design. As

shown, gun 70 may be secured to a boss 72 formed in the center of cup 60. Alternatively, a pressure-type grease fitting may be used. As is conventional in such grease guns, piston member 73 is spring-loaded, as by coil spring 75, so that when retracted by handle 77 to fill chamber 78, spring 75 is compressed. Handle 79 includes a ratchet arrangement that co-operates with notches 80 on shaft 81 so that each action of handle 79 permits piston 73 to be driven downwardly a distance of one notch-space. Grease from barrel 78 enters port 82 in boss 72 and then distributes radially through a plurality of radial bores 84 in the closed end of cup 60. Each of the radial bores 84 communicates with grease-dispensing screen 69 through a similar plurality of longitudinal bores 85 intersecting passages 84. The purpose of screen 69 is to limit the volume of grease left on the surface after the permeability test. This reduces the clean-up time after a test.

In applying the field sealer unit, a sufficient volume of grease, plastic, or other viscous material is pumped outwardly through annular screen 69 so that the space 62 between O rings 63 and 64 will be just filled. Seal face 67 is then pressed down onto the surface of concrete 10. On a hot surface, it is sometimes desirable to weight dome 60, as by manually pressing down on the top. Two passageways 86 communicate with the vapor space formed by the cup portion, or sealing chamber, 61. Taps 86 are connected to a pressure gauge and an air pressure supply chamber, as in the embodiments of FIG. 1 or 2.

In the foregoing embodiments, air is used as the fluid for measuring permeability of the sampled volume. It will be apparent that the air will contain water vapor in an amount dependent upon the temperature of the reservoir system. Other gases can be used in place of air, such as carbon dioxide, helium, nitrogen, and the like. In place of water as the vapor-displacing liquid, other liquids, such as alcohol, mercury, and the like can be substituted. Additionally, liquid permeabilities can be measured with the apparatus disclosed in FIG. 1, if such characteristic is desired or needed for a particular application.

While only a few embodiments of the present invention have been illustrated and described, various modifications in the apparatus may be made without departing from the method or the inventive concept as expressed in the appended claims.

We claim:

1. For use in an asphalt concrete permeability tester wherein a given air pressure differential is applied to a limited area of said concrete and the air flow rate is measured, a cup member including a flanged member around the rim of its open end, said flanged member including a pair of annular sealing gaskets to define an annular space for retention of a sealing material therebetween, passageways formed in the body portion of said

cup member connecting with said annular space between said gaskets, means for supplying sealing material to said passageways and a pair of air ports formed in said cup member, said ports including pipe nipples connectable thereto for attachment of flexible hoses to said permeability measuring tester.

2. Apparatus for measuring the permeability of asphalt concrete in situ and without requiring removal of samples therefrom which comprises a cup member vapor chamber having a rim sealable to a smoothed surface of the concrete and a pair of ports formed in said cup member, a portable housing adapted to be positioned in the vicinity of said vapor chamber, a liquid reservoir chamber mounted at the bottom of said housing, a pair of calibrated liquid measuring chambers mounted above said reservoir chamber and interconnected thereto by separate liquid conduits, valve means in each of said conduits for controlling flow of liquid between said reservoir chamber and each of said calibrated measuring chambers, one of said calibrated chambers being of substantially greater volume than the other of said calibrated chambers, a common vapor conduit connected to the upper ends of said calibrated chambers and valve means for regulating the flow of vapor into and out of said calibrated chambers, another vapor conduit connected to the top of said reservoir chamber, valve means in said other vapor conduit for selectively controlling vapor flow into and out of said reservoir chamber, air pump means connectable through said last-named valve means for selectively transferring liquid from said reservoir chamber to at least one of said calibrated chambers, a flow manometer positioned in said housing, flexible tube means for connecting said flow manometer to one of said ports of said cup member, and a second flexible tube for connecting to the inlet end of one of said vapor conduits whereby vapor will flow through the volume of asphalt concrete under said cup member in response to the transfer of liquid from one of said calibrated measuring chambers at a flow rate controllable by the opening of one of said valves in one of said liquid conduits to return liquid from the selected one of said calibrated chambers back to said reservoir chamber at a pressure head measurable by said manometer.
